By Myer & Co. Attn.

UNITED STATES PATENT OFFICE.

MARK W. MARSDEN, OF CONNELLSVILLE, PENNSYLVANIA.

SPOOL.

SPECIFICATION forming part of Letters Patent No. 240,436, dated April 19, 1881.

Application filed February 1, 1881. (No model.)

To all whom it may concern:

Be it known that I, MARK W. MARSDEN, a citizen of the United States, residing at Connellsville, in the county of Fayette and State of Pennsylvania, have invented certain new and useful Improvements in Spools; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to an improvement in spools and bobbins for sewing-threads; and it consists in such spools and bobbins constructed of paper-pulp and asbestos compressed into the shape of a spool by means of suitable dies, and in the dies A A, plungers B and B', cylinder C, guide D, and press-blocks E E, and in the combination and arrangement of the parts, as hereinafter more fully described.

In the drawings, Figure 1 is a plan view of my invention. Fig. 2 is a like view with section A' removed. Fig. 3 is a vertical sectional view. Fig. 4 is a detached view of section A'. Fig. 5 is a detached view of plunger B'. Fig. 6 is a similar view of plunger B, showing operation; and Fig. 7 is a view of a series of dies. A represents a die formed in sections, the parts *aa* being designed to mold the cylinder of the spool, and the more concave parts, *bb*, to stamp out the wheels thereof. The section A has cast solid therewith the pins *dd*, which are designed to fit, in practice, in the orifices *ee* in section A', to hold the sections rigidly together.

B is a plunger, rigidly secured to the side plate, *f*, and having provided therein the horizontal orifice *a'*.

The guide D has rigidly secured thereto or cast solid therewith the perforated cylinder C, and it is adjustably supported and guided by the guide-rods *b' b'*. These guide-rods are secured to the plunger-plate *f*, and project through orifices provided in the guide, and are provided with the heads *e' e'*.

The plungers B and B' are actuated by compression applied to the blocks E E.

50 The pulp is inserted in the openings pro-

vided in the dies A A, and the plungers B and B' are then forced home by pressure applied to the press-blocks E E, and as these dies are arranged together in plates, comprising a large series thereof, as shown, a large number of 55 spools are thus formed at each successive operation thereof.

The perforated cylinder C is provided with the small transverse orifices shown, to prevent the escape of moisture from the pulp when under compression, and thus to avoid injury to the outside of the spool; and in practice it is withdrawn before the plungers are removed, to prevent the breaking or fracture of the edge of the central orifice of the spool.

In the process of constructing or stamping out the spools from pulp, as aforesaid, I employ a number of dies, as shown in Fig. 7, provided in suitable bed-plates, the plates being arranged to disconnect sectionally.

The pulp may be colored, to obviate the necessity of staining or painting the spools, or the spools may be colored in the manner which ordinarily obtains in their construction.

A gloss is produced upon the spool by compression, similar to that produced by the process of calendering; and a small quantity of asbestos is also thoroughly intermingled with the pulp, to prevent combustion thereof, which cannot be accomplished with the wooden spool.

The name of the manufacturer, number of the thread, its color, quality, and the quantity contained on each spool are engraved or raised on each die or set of dies for each spool, and thereby impressed on each spool as manufactured.

My spool is designed to supersede the ordinary wooden spool and bobbin, and will effect a great saving in material and labor, and thereby greatly economize the cost of thread products for domestic or other purposes.

What I claim, and desire to secure by Letters Patent, is—

1. The die A, formed in sections *aa* and concave parts *bb*, in combination with plungers B and B', substantially as shown and described.

2. The plunger B, in combination with guide D, side plate, *f*, having therein the horizontal orifice *a'*, and blocks E E, substantially as shown and described.

3. A spool or bobbin made of asbestos and pulp, to prevent combustion thereof, substantially as shown and described.

4. The plunger B, in combination with guide D, perforated cylinder C, and die A, substantially as shown and described.

5. The plunger B, in combination with guide D and plunger B', substantially as shown, and for the purpose described.

In testimony whereof I affix my signature in presence of two witnesses.

MARK WORSNOP MARSDEN.
